COMBINED ELECTRIC CLIPPER AND VACUUM CLEANER FOR A HAIR STYLIST

John F. Wahl and Thaddeus E. Bednarski, Sterling, Ill., assignors to Wahl Clipper Corporation, Sterling, Ill., a corporation of Illinois

Filed Nov. 18, 1964, Ser. No. 82,678

Term of patent 14 years

(Cl. D22—3)

FIG. 1 is a top plan view of a combined electric clipper and vacuum cleaner for a hair stylist embodying our new design.

FIG. 2 is an elevational view of one side thereof.

FIG. 3 is an elevational view of the other side thereof.

FIG. 4 is a bottom view thereof.

FIG. 5 is a front elevational view thereof.

FIG. 6 is a rear elevational view thereof.

We claim:

The ornamental design for a combined electric clipper and vacuum cleaner for a hair stylist, as shown.
